UNITED STATES PATENT OFFICE

ROBERT RUTHERFORD ROYAL, OF PADUCAH, KENTUCKY

BINDER BOLT WRENCH

Application filed April 10, 1931. Serial No. 529,069.

My invention relates to railway rolling stock and consists particularly in a novel machine for applying and removing binder bolt nuts on the under side of a locomotive frame.

5 In locomotive construction, the pedestal binders are secured to the bottom ends of the pedestal legs after the driving boxes, axles, and wheels have been assembled with the frame, and the binders are removed occasionally when the locomotive is shopped for repairs. The binders are fastened to the pedestal legs by means of bolts and nuts, which nuts have heretofore been applied by hand. Due to the location of the binder bolts inside 10 the drivers, and their proximity to the drivers, a hand wrench cannot be easily operated and the nut may be turned only a short distance with each setting of the wrench. The application and removal of these nuts by this 15 method requires considerable time and labor.

The main object of my invention is to provide a device for quickly and efficiently applying and removing binder bolt nuts. I attain this general object, and others later appearing, by the device illustrated in the accompanying drawings in which—

Figure 1 is a side view of my invention installed in an engine pit and shows parts of a locomotive over the pit.

30 Figure 2 is a top view of my device taken on line 2—2 of Figure 1.

Figure 3 is a transverse section taken on line 3—3 of Figure 1.

Figure 4 is a vertical longitudinal section 35 taken on line 4—4 of Figure 2.

Figure 5 is a sectional view of the wrench guiding arm and telescoping fulcrum therefor.

Figs. 6 and 7 are, respectively, detail sections at 90° of the upper and lower ends of the adjustable extension arm shown in Fig. 4.

40 My binder nut wrench device includes a motor 1, shown as an air motor of well known type, a gear box 13, an extension arm including sleeve 18 and an adjustable inner member 18a, and a socket wrench 20, all supported on a cradle, to be described hereafter, which extends across the engine pit 3 and is movably mounted on tracks or guideways 4 by 45 means of wheels 5. The cradle is intended

to be pushed by the operator along the length of the pit to the desired location, but other propelling means may be provided, if desired.

The cradle includes a pair of substantially U-shaped straps or bars 6 having their upper portions rigidly secured together by longitudinal and transverse braces 7 and 7a, and 8 and 8a, respectively, and having their lower portions secured together by transverse and diagonal floor forming plates 9 and 10. A mechanism base plate 11 is pivotally mounted on the floor of the cradle at the intersection of diagonal elements 10 by means of a stud or rivet 12, and the air motor 1 and gear box 13 are rigidly secured to this plate. A dowel pin 12a is inserted through a hole in the base plate 11 and a corresponding perforation in floor member 9 to lock the base plate in its operative position. When it is desired to work on the other side of the pit, the dowel 12a can be quickly removed and the base plate swung around 180° and the locking dowel will then be positioned to co-operate with a hole 12b in the cradle 75 floor. Brace 7a is bowed outwardly to permit rotation of the wrench mechanism.

A shaft 14, having a bevel gear 15 keyed to its outer end, projects from the motor and is driven thereby, and the gear 15 meshes 80 with another bevel gear 16 inside the gear box 13. A spindle 17, rotatably mounted in the base plate of the cradle or bottom of the gear box, is keyed to gear 16 and projects up through the top of the gear box.

85 Extension arm 18 includes telescoping members 18 and 18a and has a universal joint connection 19 to spindle 17, and a similar connection with the socket wrench 20, the wrench being adapted to operatively engage 90 binder bolt nuts 21. The universal joints at each end of the telescoping arm 18 permit the socket wrench 20 to be freely moved in any direction.

95 In order to guide and control the wrench, I provide an arm 22, fulcrumed on a telescoping bar 23 which extends upwardly from the top of the gear box 13. The arm 22 has a forked end 24 pivotally mounting a 100 collar 25 which loosely surrounds the lower

portion of the socket wrench 20 and is adapted to bear against the enlarged upper portion of the wrench as the opposite end of the arm 22 is impelled downwardly by the operator. In Figure 4, a slightly modified form, collar 26 engages a groove 27 extending around wrench 25.

It will be seen that the cradle may be moved to any location longitudinally of the 10 engine pit and the wrench mechanism may be revolved to either side so that any of the binder bolt nuts may be readily reached. In disassembling the binder from an under-frame, it will usually be necessary to start 15 the nut by hand and then it may run off from the bolt by the power wrench in a fraction of the time ordinarily required. In turning a nut onto a bolt, sufficient momentum will be developed, before the nut is 20 seated, to set the nut as tightly as necessary, and the nut may be allowed to stall the motor without endangering the bolt threads or the wrench mechanism. If desired, the nut may be further tightened by hand in the 25 usual manner.

Obviously, the use of my novel device is not limited to the application and removal of binder bolt nuts, but it may be equally advantageously used in various other operations where cramped conditions prevent the effective use of hand tools. Wrenches of various types and sizes may, of course, be substituted for the socket wrench shown and described and it would also be within the 30 spirit of the invention to substitute a drill or a reamer or other rotary tool.

These and various other modifications and variations may be made without departing from the spirit of my invention and I 40 contemplate the exclusive use of all such variations as come within the scope of my claims.

I claim:

1. In combination, spaced guideways, a cradle extending between said guideways and 45 movably mounted thereon, a mechanism revolvably mounted on said cradle, a telescopic rotatable extension arm connected to said mechanism, a socket wrench on the outer end of said arm, said arm and wrench being rotated by said mechanism, said mechanism being rotatable through substantially 360 degrees to position said wrench selectively over either guideway, and at a maximum number 50 of points along the same without movement of said carriage.

2. A binder bolt wrench device including 55 a movable cradle, a telescopic extension arm rotatably supported by said cradle, means on said cradle for rotating said arm, a socket wrench having a universal joint connection with said arm, a telescopic support member, a lever fulcrumed to said member and having a forked end, and a collar pivotally mounted in said end and adapted to engage 60 said wrench, when force is applied to the

free end of said lever, to hold said wrench in operative engagement with a nut.

3. A binder bolt wrench device including a movable cradle, a revolving telescopic extension member including a socket wrench, 70 a telescopic support member, and a lever fulcrumed to said support member, said lever engaging said wrench to hold the same in operating engagement with a nut.

4. A binder bolt wrench device including 75 a base member, a telescoping extension arm rotatably supported by said member, means on said member for rotating said arm, a socket wrench having a universal joint connection with the outer end of said arm, a bar 80 rigidly secured to said member, a lever fulcrumed on the upper end of said bar and having a forked end, a collar pivotally mounted in said end and adapted to engage said wrench, when the opposite end of said lever 85 is moved downwardly, to hold said wrench in operative engagement with a nut.

5. In combination, a movable carriage, an arm extending outwardly therefrom and swingable to various positions relative thereto, a wrench on the end of said arm, means for rotating said wrench, a standard on said carriage, and a lever pivoted to said standard and engaging said wrench, said lever being adapted, upon application of pressure to the free end thereof, to position and 95 support said wrench.

6. In combination, a pit having spaced guideways, a cradle mounted on said pit and adapted to be moved longitudinally along 100 said guideways, driving mechanism rotatably mounted on said cradle, and a socket wrench projecting from said mechanism and operable thereby, said mechanism being rotatable through substantially 360 degrees relative to 105 said guideways and said wrench having a universal joint connection with said mechanism whereby said wrench may be moved to, and operated in, a maximum number of positions relative to said guideways in each 110 position of said cradle.

In testimony whereof I hereunto affix my signature this 4th day of April, 1931.

R. R. ROYAL.
